UNITED STATES PATENT OFFICE.

CHARLES C. APABLASA, OF LOS ANGELES, CALIFORNIA.

DESIGN FOR A POWDER BOX.

Application filed June 22, 1927. Serial No. 22,523. Term of patent 7 years.

To all whom it may concern:

Be it known that I, CHARLES C. APABLASA, a citizen of the United States, residing in the city and county of Los Angeles, and State of California, have invented a new and original and ornamental Design for a Powder Box, of which the following is a specification, reference being had to the accompanying drawing, forming a part hereof.

In the drawing, the figure is a perspective view of a powder box, showing my new design.

I claim:

The ornamental design for a powder box, as shown.

In testimony whereof, I hereunto affix my signature.

CHARLES C. APABLASA.
